(57) **CLAIM**

The ornamental design for an electric rotary sander, as shown and described.

DESCRIPTION

FIG. 1 is a perspective view of an electric rotary sander showing my new design;

FIG. 2 is a top view thereof;

FIG. 3 is a bottom view thereof;

FIG. 4 is a right side view thereof;

FIG. 5 is a left side view thereof;

FIG. 6 is a rear view thereof; and,

FIG. 7 is a front view thereof.

The broken lines in the drawings depict portions of the electric rotary sander that form no parts of the claimed design.
